(57) **CLAIM**

(**) Term: **14 Years**

I claim the ornamental design for a kit for converting a pair of steel posts with inwardly turned nubs into a combination pesticide duster and scratcher for livestock, as shown and described.

(21) Appl. No.: **29/180,607**

DESCRIPTION

(22) Filed: **Apr. 28, 2003**

FIG. 1 is a perspective view of a kit for converting a pair of steel posts with inwardly turned nubs into a combination pesticide duster and scratcher for livestock showing my new design;

(51) LOC (7) Cl. **08-05**

FIG. 2 is a side elevational view thereof, the elevational view of the opposing side being substantially identical thereto;

(52) U.S. Cl. **D8/373**

FIG. 3 is an end elevational view thereof, the elevational view of the opposing end being substantially identical thereto;

(58) Field of Search D8/370, 373; D30/199;

FIG. 4 is a top plan view thereof;

119/622, 652; D12/223; 248/370, 97; 47/42

FIG. 5 is a bottom plan view thereof; and,

(56) **References Cited**

FIG. 6 is a reduced perspective view showing the kit for converting a pair of steel posts with inwardly turned nubs into a combination pesticide duster and scratcher for livestock in use; the broken lines depict environmental structure for illustrative purposes only and form no part of the claimed design.
